HARMON F. FISHER, OF LONG BEACH, CALIFORNIA, ASSIGNOR TO PETROLEUM REFINING COMPANY OF CALIFORNIA, OF LOS ANGELES, CALIFORNIA, A CORPORATION OF CALIFORNIA

SYNCHRONOUS GAP POTENTIAL CONTROL FOR TREATERS

Application filed September 6, 1927, Serial No. 217,680. Renewed October 18, 1931.

This invention relates to electrical treating apparatus commonly used for de-emulsifying petroleum emulsions. A common form of apparatus used for this purpose consists of a tight container in which a grounded electrode and a live electrode insulated from the container are supported. An electric field is established in the space between the electrodes by suitable means and the emulsion consisting of petroleum and particles of water is passed through this treating space wherein the water particles are coalesced into masses of sufficient size to gravitate from the oil. The water and other residue are removed through an outlet pipe at the bottom of the container and the dry oil is taken from the container near the upper end thereof.

This invention relates particularly to an electrical dehydrator especially adapted for use in treating very "wet" emulsions; that is, emulsions having large water content. The common form of electrical dehydrator, as described above, is not suitable for treating very wet emulsions but it has been demonstrated that such emulsions may be successfully treated if the apparatus is designed to impress a high potential on the treater periodically for short durations of time. The theory of this action is that the sudden increase of potential to a very high degree will set up a local potential difference in the field between the electrodes which is sufficient to treat a small quantity of the emulsion. This action is carried on until the emulsion becomes dry enough to establish a large difference of potential entirely across the treating gap.

It is an object of this invention to provide an electrical treating apparatus in which an extremely high potential is periodically impressed on the treater.

It has been my experience that different types of emulsions treat best at different potentials; in other words, some emulsions would be treated much more efficiently if they were subjected to a constant field intensity of a certain magnitude and other emulsions would be treated best if they were subjected to a constant field intensity of a different magnitude.

It is accordingly one of the objects of this

invention to provide a treating apparatus of the character mentioned in which the magnitude of the potential impressed on the treater may be controlled.

My invention comprehends the use of a high tension reactance in the circuit of the treater. This high tension reactance may be shunted out by means of a shunt which extends around it in the circuit. Automatic means is provided for closing the shunt circuit so that the full potential produced by the transformer is impressed on the treater.

It is a salient advantage of this invention to provide a treating apparatus in which the full potential may be impressed on the treater at any point of the alternating current cycle.

Other objects of the invention and the advantages thereof will be pointed out in the ensuing description.

My invention may be best understood by reference to the accompanying drawing, in which

Fig. 1 is a diagrammatic view illustrating a preferred form of the invention.

Fig. 2 is a diagram showing a wave form of the potential impressed on the treater.

Referring to the drawing in detail and particularly to Fig. 1, the treater of the invention is designated by the numeral 11. This treater 11 has a tight shell 12 in which a grounded electrode 13 is supported by suitable straps 14. Hung on a cable 15 above the grounded electrode 13 is a live electrode 16. The cable 15 extends through an insulation bushing 17 whereby it is insulated from the shell 12. Emulsion to be treated is introduced into the lower part of the treater 11 below the grounded electrode 13 by means of an emulsion inlet pipe 19. Treated oil is withdrawn from the upper end of the treater 11 by means of an oil outlet pipe 20, and water and other residue is withdrawn from the lower part of the treater 11 by means of a drain pipe 22.

My invention utilizes an electricity supply means which is preferably in the form of a step-up transformer 25 having a primary winding 26 connected to a suitable alternating current source, and a secondary winding 27. One side of the secondary winding

27 is connected to the shell 12 by means of a conductor 28 and is consequently connected to the grounded electrode 13. This side of the secondary circuit is grounded as illustrated in the drawing. The other side of the secondary winding 27 is connected by means of a conductor 30 to a potential reducing means, preferably in the form of a high tension reactance 31. The high tension reactance 31 is connected by a conductor 33 to the outer end of the cable 15 which is electrically connected to the live electrode 16. Connected around the high tension reactance 31 is a shunt circuit 34 which has a gap 35. In parallel with the gap 35 there may also be a condenser 36. The gap 35 of the shunt circuit 34 is adapted to be closed by a closing bar 37. This closing bar 37 is adapted to be rotatably operated by a suitable motor 38, as illustrated diagrammatically in Fig. 1. When the closing bar 37 moves so that the ends are adjacent to the points of the gap 35, the high tension reactance 31 is shunted around. Shunted across the conductors 28 and 30 between the secondary winding 27 and the high tension reactance 31 is an electricity storage means in the form of a main condenser 40.

30 The operation of my invention is explained as follows:

35 The transformer 25 is excited so that a secondary current is set up in the circuit including the grounded and live electrodes 13 and 16. The potential at the electrodes is considerably less than the potential at the secondary winding of the transformer because of the action of the high tension reactance 31 which chokes back the voltage. The emulsion to be treated is introduced into the tank 12 by the emulsion inlet pipe 19, and it passes between the electrodes 13 and 16 where an electric field is set up. The emulsion which this treater is adapted to treat is very wet and has a large water content, the water particles thereof tending to chain up so as to short-circuit the electrodes. This chaining up action reduces the potential between the electrodes by permitting a heavy flow of current. In the ordinary treater a heavy flow of current is drawn until the short-circuiting of chains of masses of water are broken in some manner.

40 In my invention the treating action is as follows:

45 The condenser 40 which is connected across the wires 28 and 30 is stored with electricity. The potential difference between the wires 30 and 33 adjacent to the high tension reactance 31 is considerable by reason of the reactance 31, and the difference in potential between the points of the gap 35 is also considerable. When the particles of water in the emulsion chain up between the electrodes and tend to draw a heavy current, the difference in potential of the opposite sides of the high

tension reactance 31 and of the points of the spark gap 35 is considerably increased and the result is that there is a tendency for a spark to jump across the gap 35 and shunt out the high tension reactance 31. The gap 35, however, is too large and there will be no 70 sparking. The motor 38 being in operation rotates the closing bar 37. When the closing bar 37 moves into closing position, in which position the ends are adjacent to the points of the gap 35, the shunt circuit 34 will be closed and the high tension reactance 31 will be shunted out. This provides a path around the high tension reactance and the electricity which is stored up in the main condenser 40 75 may flow to the treater, establishing a great potential difference between the two electrodes 13 and 16. This sudden rise in potential difference is sufficient to cause a high localized potential gradient in the treating gap between the electrodes and sufficient to treat a small amount of emulsion. I have found that better results are obtained when the condenser 36 is used than when it is not, this condenser tending to produce a more 80 sudden rise of potential. This condenser 36, however, is not indispensable.

85 Referring to Fig. 2, the numeral 41 represents a wave form of the potential which is impressed on the treater 11. The ordinary wave form is indicated by dotted lines 42 and is the potential ordinarily impressed on the treater with the high tension reactance included in the circuit. When the shunt circuit 34 is closed and the high tension reactance 31 90 is shunted from the circuit, a high potential peak 43 occurs having an extremely steep wave front, which of course denotes an instantaneous increase in potential. The duration of the peak 43 is ordinarily very short and is usually very high so that the effect on the emulsion is such as to treat a small amount thereof. This instantaneous rise in potential is absolutely necessary in order to establish a localized difference in potential of a potential gradient sufficient to have a de-emulsifying effect on the emulsion.

95 The duration of the wave peaks 43 is readily increased or shortened by the sizes of the end faces of the closing bar 37. I prefer to operate the closing bar 37 synchronously with the secondary current, but it should be understood that the shunt circuit 34 need not be closed every alternation or every cycle, but may be closed whenever desired by controlling the rate of rotation of the closing bar 37.

100 As previously explained, it may be desirable to change the magnitude of the peak 43 and use a lower potential than that shown in Fig. 2. This is accomplished by causing the closing bar 37 to close the shunt circuit 34 at a different point on the sine wave 42.

105 This invention is an improvement over the inventions described in my copending applications, one entitled Method of dehydrating

emulsion, filed August 30, 1926, Serial No. 132,375, and the other entitled Dehydrated apparatus using high tension reactance, filed September 9, 1926, Serial No. 134,476.

5 I claim as my invention:

1. In an apparatus for dehydrating emulsion, the combination of: a pair of electrodes; an electricity supply means for supplying electricity to said electrodes; potential reducing means for reducing the potential impressed on said electrodes; and mechanically operated shunting means for shunting out said potential reducing means.

10 2. In an apparatus for dehydrating emulsion, the combination of: a pair of electrodes; an electricity supply means for supplying electricity to said electrodes; a reactance for reducing the potential impressed on said electrodes; and mechanically operated shunting means for shunting out said potential reducing means.

15 3. In an apparatus for dehydrating emulsion, the combination of: a pair of electrodes; an electricity supply means for supplying electricity to said electrodes; potential reducing means for reducing the potential impressed on said electrodes; mechanically operated shunting means for shunting out said potential reducing means; and an electricity storage means connected to said

20 supply means.

25 4. In an apparatus for dehydrating emulsion, the combination of: a pair of electrodes; an electricity supply means for supplying electricity to said electrodes; a reactance for reducing the potential impressed on said electrodes; mechanically operated shunting means for shunting out said reactance; and an electricity storage means connected to said supply means.

30 5. In an apparatus for dehydrating emulsion, the combination of: a pair of electrodes; an electricity supply means for supplying electricity to said electrodes; potential reducing means for reducing the potential impressed on said electrodes; a shunt circuit around said potential reducing means, said shunt having a gap; and means for closing said gap for periodically closing said shunt.

35 6. In an apparatus for dehydrating emulsion, the combination of: a pair of electrodes; an electricity supply means for supplying electricity to said electrodes; a reactance for reducing the potential impressed on said electrodes; a shunt circuit around said reactance, said shunt having a gap; and means for closing said gap for periodically closing said shunt.

40 7. In an apparatus for dehydrating emulsion, the combination of: a pair of electrodes; an electricity supply means for supplying electricity to said electrodes; potential reducing means for reducing the potential impressed on said electrodes; a shunt circuit around said potential reducing means,

said shunt having a gap; means for closing said gap for periodically closing said shunt circuit; and an electricity storage means connected to said supply means.

45 8. In an apparatus for dehydrating emulsion, the combination of: a pair of electrodes; an electricity supply means for supplying electricity to said electrodes; potential reducing means for reducing the potential impressed on said electrodes; and shunting means for said potential reducing means and driven in synchronism with the electricity supplied to said electrodes.

50 9. In combination: a pair of electrodes; supply means for supplying electricity to said electrodes; a potential reducing means for reducing the potential supplied to said electrodes to a fraction of the potential of said supply means; means operating in synchronism with said potential of said supply means for successively shunting said potential reducing means; and means cooperating with said potential reducing means to form an oscillating potential when the synchronously driven means shunts said potential reducing means.

55 10. In an apparatus for treating an emulsion, the combination of: a pair of electrodes between which is positioned the emulsion to be treated; a supply means for impressing a potential difference between said electrodes; circuit means for connecting said supply means to said electrodes; a potential reducing means connected to said circuit means and through which moves the current reaching said electrodes whereby the voltage drop across said potential reducing means decreases the potential applied to said electrodes; and a synchronous gap connected around said potential reducing means and driven in synchronism with the current supplied to said electrodes for periodically shunting said potential reducing means.

60 In testimony whereof, I have hereunto set my hand at Los Angeles, California, this 26th day of August, 1927.

HARMON F. FISHER.
